S. ZIDO

TOILET PAPER ROLL SECURING DEVICE

Filed April 18, 1927

FIG]

卷之二

十一

INVENTOR
Stephen Zido

BY
Jolanta H. Polachek
ATTORNEY

UNITED STATES PATENT OFFICE.

STEPHEN ZIDO, OF RICHMOND HILL, NEW YORK.

TOILET-PAPER ROLL-SECURING DEVICE.

Application filed April 18, 1927. Serial No. 184,599.

This invention relates to a holding device for toilet paper, and its object is to provide an article of this character which is adapted to be installed in conjunction with a recessed wall, and when so installed to permit of the easy attachment of a roll of the said paper and to further permit of the removal of the empty core, if any, when the supply of the said paper has been entirely exhausted.

10 Further objects are, a neat and efficient means for the attachment of the device, simplicity in its construction, and low cost of manufacture.

These and other objects and features will 15 be fully described in the following specification and illustrated in the accompanying drawings, in which:—

Fig. 1 shows a front view of the holder installed in a wall recess, some parts being 20 shown in section and a portion of the wall broken away to more clearly disclose the construction of the various parts.

Fig. 2 shows a plan view in section on the line 2—2 of Figure 1.

25 Fig. 3 shows an end view, the recess being shown in section on the line 3—3 of Figure 1.

Fig. 4 shows an enlarged fragmentary view of a portion of Figure 1, but with a modification of the invention applied thereto.

30 Referring now to Figure 1 of the drawings, the device 10 is shown installed within the recess 11 of the wall 12. The walls 13, 14 of the recess being of the form and construction commonly used for this purpose.

35 Front and back plates 15 and 16 are clamped against the wall 13 by means of the screws 17 and 18 which engage threads in the said back plate. A tube 19 is secured to the front plate at 20 and extends back behind the front wall passing through the plate 16.

40 This tube is slotted as shown at 21 and is provided with an end cap 22 which is attached by the pins as seen at 23 and 24. The sliding element 25 comprises a push rod 26,

45 a connecting bar 27, and a slide bolt 28 which has a hole 29 in its face end. This sliding element is supported by the tube 19 and has its connecting bar 27 projecting upward through the slot 21. A spring 33 bears

50 against its rear extremity and is adapted to maintain it in its normal position, and to drive it forward when released from pressure when in use. These supporting and working parts may be constructed of brass, or of any

55 suitable material, and the sliding element

may be cast in one piece, or of assembled parts, as desired.

A stationary plate 34 is affixed to the wall 14 as shown and is provided with a lug 35 which has a central hole 36. An arbor of 60 the usual form is shown at 40 having end pins 41 and 42 which engage the holes 29 and 36. A roll of paper 43 is shown supported on the arbor 40 in the customary way.

Experience has shown that the attaching 65 of a supporting arbor with a roll of paper in position within a wall recess as ordinarily constructed, is a difficult and annoying procedure, by reason of the difficulty in extending the fingers between the side wall and the 70 paper roll to insert the arbor pins in the receiving holes.

The device herewith shown and claimed, 75 obviates this difficulty by providing the push rod 26 which, when pressed inward, draws back the element 28 and gives the desired clearance for centering and inserting the pins on the ends of the arbor.

The modification illustrated in Figure 4 discloses a tube 19' housing the push rod 26, 80 and the tube is formed with a dove-tailed groove 45 engaging a dove-tailed tongue 46 on a slide 47 formed with rack teeth 48, and normally urged in one direction by an expansion spring 49 acting between 85 the slide and the plate 16. A support 50 projects from the tube 19', and holds a shaft 51 carrying a pinion 52 meshing with the rack 48, and also carrying a ratchet wheel 53 engageable by a pawl 54 projecting from 90 a stand 55 fastened to the plate 16. The shaft 51 may be turned upon the lifting of the pawl 54 from the ratchet wheel, and the pinion 52 moves the slide 47 changing the length of the acting slot 21 and determining 95 the abutting point bar 27, which adjusts the amount that the front of rod 26 projects from the front of the tube 19'. The pawl 54 normally holds ratchet 53 from turning due to the action of expansion spring 100 49, and the slide 47 is therefore held as placed.

While I have shown and described the invention in its preferred form and manner of installation, it is understood that I do not 105 confine myself to the exact details thereof as illustrated, but claim the right to such minor modifications as may come within the scope of the appended claims.

Having thus described my invention, 110

what I claim as new and desire to secure by Letters Patent, is as follows:

1. In a device of the character described, the combination of a supporting structure, 5 a slideable bolt therein mounted having an aperture in the end thereof, a push rod connected with and adapted to co-act with the said slideable bolt, a spring element bearing against the said push rod and adapted to 10 exert a forward stress thereon, and a receiving socket adapted to co-act with the said slideable bolt to support an arbor rotatably therebetween.
2. In a device of the character described, 15 a pair of plates clamped together on opposite sides of a wall structure, a tubular member passing through said plates, a push rod within the said tubular member, a spring within the said tubular member and bearing against the said push rod for urging 20 the same outwardly, a slide bolt connected to said push rod, a receiving hole in the face end thereof, and having a socket plate mounted in opposition to the said slide bolt 25 and adapted to co-act therewith to rotatably support an arbor element.
3. In a device of the character described, 20 supporting plates clamped in position on opposite sides of a wall structure, a tube having a slot therein disposed through 25 apertures in said plates and extending rearwardly therefrom, a push rod within the

35 said slotted tube, a spring adjacent said push rod and bearing against the same, a bolt having a receiving hole in one end thereof slidably mounted in registering apertures in said plates, a bracket disposed through the slot of said tube and rigidly attached to said push rod and to said bolt, 40 a receiving socket mounted in opposition to the aforesaid bolt, and an arbor rotatably mounted between the end of said bolt and said receiving socket.

4. In a device of the character described, 45 supporting plates clamped in position on opposite sides of a wall structure, a tube having a slot therein disposed through registering apertures in said plates and extending rearwardly therefrom, a push rod within the said slotted tube, and a spring 50 within said tube engaged against the said rod, a slide bolt having an aperture therein disposed through apertures in said plates and connected with the said push rod, means for adjusting the amount of projection of the said push rod from the tubular member, a receiving socket mounted in opposition to the aforesaid bolt, and a rotatable arbor adapted to be supported between 55 the two.

In testimony whereof I have affixed my signature.

STEPHEN ZIDO.
